Primary Examiner — Elizabeth Albert*(74) Attorney, Agent, or Firm* — Christensen O'Connor Johnson Kindness PLLC(57) **CLAIM**

The ornamental design for a pen, as shown and described.

DESCRIPTION

FIG. 1 is an upper front right perspective view of a pen showing my new design, with a flexible clip attached to the body of the pen;

FIG. 2 is an upper front left perspective view thereof, with the flexible clip alternately attached to a push button of the pen; FIG. 3 is a front elevation view of the pen shown in FIG. 1; FIG. 4 is a rear elevation view thereof;

FIG. 5 is a right side elevation view thereof, with the left side elevation view being a mirror image of the right side elevation view;

FIG. 6 is an enlarged top plan view thereof; and,

FIG. 7 is an enlarged bottom plan view thereof.

The stippling shown in FIGS. 1-7 represents a surface texture.
